UNITED STATES PATENT OFFICE.

EDWIN CLAY, OF RENO, NEVADA.

RAIL-BRACE.

1,319,461.

Specification of Letters Patent.

Patented Oct. 21, 1919.

Application filed April 16, 1918. Serial No. 228,936.

To all whom it may concern:

Be it known that I, EDWIN CLAY, a citizen of the United States, residing at Reno, in the county of Washoe and State of Nevada, have invented certain new and useful Improvements in Rail-Braces, of which the following is a specification.

My invention relates broadly to the class of railway ties and more particularly, to an improved bracing tie.

The primary object of the invention is to provide a rail brace and tie which will, when assembled and applied to a rail, eliminate the spreading of the rails, which has heretofore caused numerous disastrous wrecks and the like; one which will also, greatly lessen the danger of broken rails, inasmuch, as the brace will become a tie that binds effectively, and each rail will serve to support its complemental or adjacent rail.

The invention also contemplates the provision of a device of the character described, which may be not only used in conjunction with rails, but may, at the option of the user, be effectively applied as a brace for split rail switch bars.

Another important characteristic of the invention, resides in the provision of a combined tie and brace, which may be readily applied to a rail or the like, without the necessity of driving spikes or the like into the usual supporting ties.

Other improvements and novel details in the construction and arrangement of the various parts of the construction will be brought out more in detail in the description to follow, which, for a clear understanding of the invention should be considered in connection with the accompanying drawings, forming a part thereof and wherein is disclosed, for the purpose of illustration, a convenient and satisfactory embodiment of the invention.

In the drawings:

Figure 1 is a side elevation;

Fig. 2 is a perspective of the connecting and bracing element;

Fig. 3 is a perspective of the rail chair;

Fig. 4 is a side elevation of a slightly modified form;

Fig. 5 is a detail in perspective of the connecting and bracing element;

Fig. 6 is a perspective of a modified form wherein the device is used in conjunction with split rail switch bars; and

Fig. 7 is a still further modification of the

device as used in conjunction with a stub switch bar.

Referring now more particularly to the drawings, wherein like reference numerals, 60 designate like or corresponding parts throughout the several views thereof, it may be stated, in describing the preferred embodiment of the invention, that the device comprises rail chairs, generally numbered 1, 65 which chairs have arranged upon their outer extremities, angularly disposed bracing and tying elements 2, which elements are provided with recesses 3; the purpose of which shall be hereinafter more fully described. 70 The chair 1 extends for a distance beyond the base of the rail and has arranged thereupon, adjacent the outer extremity of said extension, a connecting bar 4, substantially 75 T-shaped in cross section and arranged in parallelism with the bracing member 2.

In order to provide for means whereby the rails 5 may be securely held against lateral movement upon their respective chairs, a connecting and bracing element 6, is supplied. This element is constructed from a single piece of material, such as soft steel or the like and is of such width as to accord with the distance between the rails 5. Upstanding flanges 7 and 8, are arranged upon 85 the opposite extremities of said connecting and bracing element 6 and a portion of said element is cut away, adjacent said extremities, as at 9 and 10, whereby the upstanding flanges 7 and 8, may be readily engaged 90 with the web portions of the rails and also conform to the shape thereof. Under cut grooves 11 and 12 are provided in the connecting element 6 and extend longitudinally thereof, so as to be readily engageable with 95 the connecting bar or rib 4. In assembling the device, it is only necessary that the undercut grooves 12 and 13 be engaged with their respective connecting ribs 4, whereupon the upstanding flanges 7 and 8 will 100

engage with the web portions of the rails 5. To provide for means whereby longitudinal movement of said connecting and bracing element 6 will be presented, I provide in the upstanding flanges 7 and 8, apertures 105 14, complementally disposed to the apertures 3 in the rail chair. Bolts 15 are then passed through the registering apertures and through suitably arranged openings in the web portions of the rails, whereupon a fastening nut or the like as at 16 is turned 110 upon the threaded shank of the bolt.

The foregoing construction, is particularly adaptable for use in conjunction with railway tracks newly laid, and, in order to provide a connection which may be readily applied to railway tracks, previously laid, I have proposed the construction as shown to advantage in Figs. 4 and 5 of the drawings.

In this particular construction, rail chairs 1, with the usual connecting bars or ribs 4 are supplied, the construction deviating from that heretofore described, by the provision of a sectional connecting and bracing element, designated in its entirety, as at 17. This sectional connecting and bracing element consists of members 18 and 19, the said members having provided upon their opposite extremities, upstanding rail engaging flanges 20 and 21, the under faces of the elements 18 and 19 being cut away as at 22 and 23, to provide for insertion of the rail base. The adjacent extremities of the said elements 18 and 19, are reduced as at 24 and 25, to provide substantially overlapping portions. Upon the reduced portion 24, I provide a T-shaped connecting rib 26, which rib is received by an undercut groove 27 formed in the overlapping or reduced portion 25. It may be also stated, for convenience in reading the drawings, that the members 18 and 19 are provided with longitudinally extending grooves 28 and 29, similar to those as designated at 12 and 13. These grooves 28 and 29 are adapted to receive the longitudinally extending connecting ribs 4 therein.

In applying the construction as disclosed by this modification, it is only necessary that the chairs 1 be inserted beneath the rail and that the connecting elements 18 and 19 with their longitudinal grooves 28 and 29 be engaged with the complementally disposed connecting rib 4, while the rail engaging flanges 20 and 21 will efficiently brace the web thereof. With the parts thus connected, a connecting rib 26 as carried by the reduced portion 24 is moved into engagement with the undercut groove 27 as arranged in the reduced portion 25. It will be evident, by this construction, spreading of the rail will be prevented and the rail engaging flanges 20 and 21 will efficiently serve as bracing elements.

The two forms of my invention as above described, disclose the same as being applied to a rail and serving as a bracing and tying means. It is to be understood, however, that these forms, are not of the essence of my invention and that the same may be readily used as a connecting and bracing element for use in conjunction with a split rail switch and also, as a connection for use in conjunction with stub switch bars, the modifications being illustrated to advantage, by Figs. 6 and 7.

Referring now to the split rail switch connection, the usual base or supporting plate 30 is provided having arranged thereupon, at a point preferably beyond the opposite ends thereof, longitudinally arranged T-shaped connecting ribs 31. The supporting plate 30 has also, at its outer or opposite extremities, suitable openings as at 32 and 32', whereby operation of the supporting plate will be facilitated. A connecting element 33, having longitudinally extending undercut grooves 34 is receivable upon the supporting plate 30, the said longitudinal grooves being adapted for engagement with the T-shaped connecting ribs 31, whereby connection between the elements 30 and 33, may be afforded. Flanges 35 and 36 are formed upon the opposite ends of the connecting element 33 and are so arranged as to engage the switch points 37 and 38 which are in turn, secured thereto, by means of bolts 39 and 40, which are passed through suitable transversely arranged openings in the flanges and similarly arranged openings in said switch points 37 and 38. To prevent longitudinal movement of the connecting element 33, a bolt 41 is passed through the supporting element 30 and the connecting element 33 whereupon a nut is turned into engagement therewith, thus securely holding the connecting element 33 against movement.

The stub switch bar connection as shown to advantage in Fig. 7, comprises a substantially chair-like construction, as at 42, the said chair comprising an angularly disposed rail engaging flange 43 and a longitudinally arranged T-shaped connecting rib 44. A laterally extended arm 45 is arranged upon the chair construction and may have arranged therein, a suitable opening, not shown, whereby connection may be had with a suitable operating member.

Other modes of applying the principle of my invention may be employed instead of those explained, change being made as regards the construction herein disclosed, providing the means stated by any of the following claims or the equivalent of such stated means be employed.

I, therefore, particularly point out and distinctly claim as my invention:

1. A rail tie, comprising rail receiving and supporting chairs, parallel undercut ribs arranged upon the adjacent portions of said chairs, a sectional connecting element engageable with said chairs for holding the same in spaced relation, said connecting element including a plurality of sections, the adjacent ends of said sections having suitable connecting means arranged thereupon, complementally formed grooves arranged in said sections adapted to receive said ribs, and rail engaging flanges formed upon the opposite extremities of said sections.

2. A rail tie, comprising rail receiving and supporting chairs, parallel undercut ribs arranged upon the adjacent portions of said chairs, a connecting element engageable with 5 said chairs, for holding the same in spaced relation, said connecting element including a plurality of sections, the adjacent ends of said sections being reduced, an undercut rib arranged upon one of said reduced portions, 10 a complementally formed groove arranged upon the remaining portion and engageable with said undercut rib, complementally formed grooves arranged in said sec-

tions and adapted to receive said first mentioned ribs, rail engaging flanges formed 15 upon the opposite extremity of said sections, and means engageable with said flanges and said chairs for preventing longitudinal movement of said sections.

In testimony whereof I affix my signature in presence of two witnesses.

EDWIN CLAY.
